UNITED STATES PATENT OFFICE.

JOHN WEST, OF BROOKLYN, NEW YORK.

DESIGN FOR TYPE.

SPECIFICATION forming part of Design No. 18,829, dated December 25, 1888.

Application filed November 8, 1888. Serial No. 290,336. Term of patent 7 years.

To all whom it may concern:

Be it known that I, JOHN WEST, a citizen of the United States, residing at Brooklyn, in the county of Kings and State of New York, 5 have invented a certain new and original Design for a Font of Printing-Type; and I do declare the following to be a full, clear, and exact description of the invention, such as will enable others skilled in the art to which it applies to make and use the same, reference being had to the accompanying typographical impression, and to the letters and figures marked thereon, which form part of this specification.

15 My design consists of an ornamental letter displaying a sharp contrast between hair-lines and heavy lines, each set of lines terminating in lines of the opposite order, (*i. e.*, the heavy lines diminish to a point or points and the hair-lines widen to a cusp-like termination,) and in general all the lines running from the left downward toward the right being heavily shaded and those running from the right downward toward the left being hair-lines.

20 The vertical lines of B, D, E, F, II, I, J, K, L, O, P, Q, R, T, a, b, d, f, h, i, j, k, l, m, n, p, q, r, t, u, 1, 4, 7, 9, and ! are heavy lines and terminate as shown. The left vertical of M, the verticals of N, the right vertical of U, and 25 those of the \$ are hair-lines with the terminations shown. The horizontal lines and those approximately so in all the letters are hair-lines, terminating in the curves shown, except

g, 7, 4, and the —, in which they are heavy. The upper horizontal line of A terminates in 35 the short downward curve. The upper curves of C and G terminate in the downward curve and dot, as shown. B, D, P, R, a, b, d, k, p, 40 8, and 0 have re-entrant curves terminating in reversed cusps, as shown. The cross-bar 40 of K, the vertical portion of the tail of Q, the cross-line of f, and one of the lines of the tail of g are hair-lines ending with the curve and dot, as shown. The numeral 0 is not closed at the top, but has the re-entrant curve above 45 described. The letters O and o are so closed. G, H, I, K, N, Q, M, R, &, a, f, g, h, j, k, m, n, 50 p, q, t, u, y, 3, 4, and 7 extend below the line, and v and w extend above the line, in addition to those lower-case letters which are required so to do. The punctuation-marks harmonize with the remaining characters.

What I claim as new is—

The design for a font of printing-types, comprising upper and lower case letters, numerals, and punctuation-marks, which consists of hair-lines and heavy lines, each line terminating in a line of the opposite order, and the individual members of the design having the characteristics shown and described.

In testimony whereof I affix my signature in presence of two witnesses.

JOHN WEST.
